UNITED STATES PATENT OFFICE.

JOSEPH CROSSLEY, OF TRENTON, NEW JERSEY.

DRIVING MECHANISM.

Original application filed December 9, 1920, Serial No. 429,478. Divided and this application filed March 22, 1921. Serial No. 454,367.

To all whom it may concern:

Be it known that I, JOSEPH CROSSLEY, a citizen of the United States, residing at Trenton, in the county of Mercer and State 5 of New Jersey, have invented certain new and useful Improvements in Driving Mechanism, of which the following is a specification.

This invention relates to driving mechanism 10 for use in connection with washing machines, and is adaptable particularly to the washing machine illustrated and described in my copending application for Letters Patent, Serial Number 429,478, filed December 9, 1920, of which the present application is a division.

The primary or general object of the invention is to provide gearing of an improved 20 nature for developing the energy of a motor or other power source into rotary movement and transmitting such movement to the clothes containing cylinder of the washing machine.

A further object of the invention is to provide 25 mechanism for the purpose stated which operates automatically at predetermined cycles of movement for reversing the direction of rotation of the cylinder.

A further object is to provide shifting 30 mechanism of improved nature for automatically causing the driven shaft to be alternately reversed at certain intervals, the said mechanism being of such construction and operation that smooth uninterrupted action 35 of the parts is at all times assured, with the possibility of breakage, wear or derangement of any of the parts being remote.

A still further object of the invention includes the improved manually controlled 40 clutch mechanism, which in a facile manner, enables the operator of the machine to instantly and accurately control the movements and operation of the latter.

With these objects in view, together with 45 others which will appear as the description proceeds, the invention consists in the novel construction, combination and arrangement of parts, all as will be described more fully hereinafter, illustrated in the drawings, and 50 particularly pointed out in the claims.

In the drawings:

Fig. 1 is a vertical longitudinal sectional view taken through driving mechanism embodying my invention the view showing the

mechanism as applied to a conventional 55 washing machine.

Fig. 2 is an enlarged detail sectional view 60 illustrating the manner in which power is transmitted from the motor to the power gears,

Fig. 3 is a detail elevation of the gearing employed for transmitting power from the power gears to the cylinder operating mechanism,

Fig. 4 is a view similar to Fig. 6, and 65 showing the mechanism changed to such position as will cause the cylinder to rotate in reverse direction;

Fig. 5 is a sectional view taken substantially upon line 5—5 of Fig. 3, 70

Fig. 6 is a vertical sectional view taken on line 6—6 of Fig. 5, and

Fig. 7 is a horizontal sectional view taken on line 7—7 of Fig. 3.

As the improved gearing disclosed herein 75 is primarily for use in connection with washing machines it will be described as adapted to that use, but it will be understood that such association is not to be considered as a limitation of the invention to such use, as the 80 invention is applicable to a variety of machines or mechanisms where alternating rotary driving movements are required.

A wall of the wash tub is indicated generally at 25, and to this wall and upon the interior of the tub a motor 30 is secured. This motor is enclosed by a water tight casing, and the shaft 31 of the motor, which extends transversely into the tub, is provided with a suitable packing gland to preclude 90 the entrance of water to the interior of the motor case. The motor, as will be understood, will be energized by being wired with a suitable source of electrical energy, and the 95 operation of the motor is controlled by the push button switch indicated at 35 arranged in the base of the motor.

The power gearing for the washing machine is confined within a casing 36 disposed within the tub and secured to one end wall 100 thereof adjacent to the motor 30 and below the plane of the latter. The outer end of this casing terminates in an annulus 37 which has arranged therein a worm gear 38. This worm gear is engaged by a worm 39 105 driven by the shaft 31 of the motor. In the present instance, the worm is disposed beneath a cup 40 to receive a suitable lubricant,

and this cup is sealed tightly by a suitable cap or cover as shown.

The outer end of the casing 36 is closed by a housing 59, the inner end of which is of equal diameter with and engages the edges of annulus 37. Screws or bolts may be employed for securing this housing to the casing, and it will be understood that a water tight connection between the casing 10 and housing must be established. The housing has arranged centrally therein a shaft 60, the said shaft being alined with the central opening 61 in the worm gear 38. The shaft 60 is hollow and receives a slideable 15 clutch carrying rod 62 extending throughout the length of the said shaft. The inner end of this rod carries a clutch member 63 adapted to engage with the clutch face 64 carried by worm gear 38, and when the rod is retracted this clutch member is withdrawn from the said clutch face and is confined within the head 65 at the extreme inner end of shaft 60. As shown particularly in Figs. 1 and 2 of the drawing, the gear 38 has a 20 central opening to receive the head 65. The rear face of the gear 38 has secured thereto a plate, as indicated in Fig. 1, and this plate is provided with the clutch face 64 to receive the clutch member 63 carried by the rod 62. When the rod is moved to its limit in one direction, the clutch member 63 will 25 protrude from head 65 and engage with the clutch face 64 of the plate, whereby a positive drive connection is established between gear 38 and the head 65, while retraction of the clutch member 63 from face 64 breaks this power connection and the said member is then wholly housed by the head 65. The outer end of the rod 62 is provided with a 30 grooved head 66 which is engaged by a pin carried by arm 67 connected to operating rod 68. This rod is mounted in suitable bearings in housing 59 and protrudes at one end to the exterior of the housing. The protruding end of the rod is equipped with a handle 69 to enable the same to be readily operated.

The hollow shaft 60 is provided inwardly from its ends with a worm 70 engaged by worm wheel 71 carried by the worm shaft 72 disposed transversely of the housing. This worm shaft has also secured thereon a cam wheel 73, having cam surfaces 74-75 at its outer edges and upon the opposite faces of the said wheel. These cam surfaces extend 55 throughout substantially 180° of the wheel, as shown, and are adapted as the wheel rotates to alternately engage with rollers 76 mounted upon upstanding pins 77 secured in spaced relation upon the gear shifting bar 78.

The gear shifting bar is mounted in suitable bearings within the housing and disposed transversely thereof, and has a recess 79 in one face thereof to receive a lug 80 60 projecting laterally from the upper edge of

the rocker plate 81. This rocker plate is supported at its lower end by a bushing 82 extending forwardly from the same and fitting within bearing 83 in the forward face of the housing. The bushing 82 receives 70 and rotatably supports the rotatable cylinder operating shaft 84, the forward end of which is squared as at 85 to engage with the cylinder socket, while the inner end of the said shaft has a spur gear 86 affixed thereto. The rocker plate 81 has trunnions 87, 88 and 89 projecting therefrom, and upon which are rotatable pinions 90, 91 and 92; the trunnions 87-89 being so disposed that the pinions 90-92 carried thereby are at all 80 times in mesh with the gear 86, while trunnion 88 is so disposed that the pinion 91 carried thereby is in mesh with pinion 92. The pinions 90-91 are adapted to be brought alternately into mesh with gear 93 secured 85 to shaft 60. This movement of the gears is caused by operation of the rocker plate 81 through instrumentality of cam wheel 73, as will be understood. It is apparent that by the arrangement of pinions 91-92, the 90 direction of rotation of gear 86 will be reverse of that derived through the instrumentality of pinion 90 in mesh with gear 93.

Assuming the socket 94 of the clothes containing basket or cylinder in the tub to be 95 engaged with the squared forward end 85 of shaft 84, the clutch rod 62 may be operated so as to move the clutch head 63 thereof into engagement with clutch face 64 carried by the worm gear 38. The mechanism within the housing at once becomes active, and the hollow shaft 60 at once begins to rotate, and the cylinder operating shaft will 100 rotate in one direction or the other, depending upon which of the gears 90 or 91 is engaged with the gear 93. As the hollow shaft 60 rotates, the worm wheel 70 is turned, as is cam wheel 73. As the cam wheel continues to turn, one of the cam faces thereof will move out of engagement with its cooperating roller 76, while the cam face upon the opposite side of the wheel will contact with its cooperating roller, and through the instrumentality of the pin 77 supporting said roller, will force the gear shifting bar 105 to move, said movement causing rocker plate 81 to correspondingly move. This movement of the rocker plate disengages from gear 93 the pinion which has heretofore been in mesh therewith, and causes the said gear 110 93 to be engaged by the pinion which has heretofore been idling. This shifting of the rocker plate therefore causes the direction of rotation of the shaft 84 to be reversed, and it will be understood that this operation continues so long as the motor is energized 115 and the clutch is not withdrawn. While in the present instance, for simplicity in illustration, there is shown upon the cam wheel 73 but one cam face on each side thereof, 120

125

130

it will be understood that two or more of such faces may be provided if desired, and it will be understood further that the periodic number of rotations in opposite directions of shaft 84 may be controlled by increasing or decreasing the length of the said cam faces on the opposing faces of wheel 73.

The clothes containing cylinder or basket 10 is indicated diagrammatically at 95, and it will be understood that this cylinder may be of any preferred type or style and may be rotatably mounted in any desired manner in the tub.

15 From the foregoing, it is obvious that I have provided mechanism fully capable of carrying forth the objects mentioned above for which it is particularly adapted, and although the above is a description of the 20 invention in its preferred embodiment, it will be understood that the invention is not to be limited to the precise structure or use set forth, as variations in adaptability and detailed arrangement may be resorted to if 25 desired without departing from the invention as defined by the claims.

I claim:—

1. In a device of the class described, a source of power, a cylinder drive shaft, a 30 gear driven by said source of power, a gear on said cylinder drive shaft, a movable plate, idler gears on said plate in mesh with the gear on said cylinder drive shaft for transmitting motion thereto in reverse directions 35 from the power driven gear, a cam wheel operated by said power gear, a slide bar actuated by said cam wheel and engaging said plate, and rollers on said slide bar in the path of travel of said cam wheel.

40 2. In a device of the class described, a source of power, a cylinder drive shaft, a gear on said drive shaft, a power gear operated by said source of power, clutch mechanism between said power gear and said 45 source of power, means for operating said clutch mechanism, a worm operated by said power gear, a cam wheel driven by said worm, a rocking plate, idler gears on said rocking plate in mesh with the gear on said 50 cylinder drive shaft and adapted alternately upon rocking of said plate to be brought into mesh with said power gear, a sliding bar connected to said plate, and pins on

said bar adapted to be engaged by the cams of said cam wheel. 55

3. In a device of the class described, a source of power, a worm driven by said source of power, a worm wheel driven by said worm, a clutch face on said worm wheel, a power shaft alined with said clutch face, a rod extending through said power shaft, a clutch head on said rod adapted to be engaged with said clutch face, and a cylinder drive shaft adapted to be driven from said power shaft. 65

4. In a device of the class described, a source of power, a worm wheel driven by said power source, a clutch element carried by said worm wheel, a power shaft, a clutch head carried by said power shaft and 70 adapted to be moved into or out of engagement with said clutch element, means for moving said clutch head, a cylinder operating drive shaft, a gear on said drive shaft, a rocking plate movable concentric with said cylinder drive shaft, idler gears on said plate in mesh with the gear of said cylinder drive shaft, a gear on the first mentioned drive shaft adapted to be engaged alternately by said idler gears, and means governed by the rotation of said first mentioned power shaft for rocking said plate. 80

5. In an alternating drive gearing, a power member, a shaft driven by said power member, a gear driven by said shaft, 85 a rocking plate, pinions on said plate adapted to be alternately engaged with said gear, a spur gear driven by said pinions, a slide bar, a connection between said slide bar and said plate whereby the latter will 90 be rocked by sliding movements of the former, a cam wheel operated from said shaft, and pins on said slide bar in the path of the cams of said cam wheel.

6. In an alternating drive mechanism, a 95 power member, a clutch face on said member, a shaft, a pin slidable longitudinally in said shaft and coupled therewith, a clutch head carried by said pin and adapted to engage with said clutch face, means for 100 moving said pin, a gear carried by said shaft, and pinion mechanism adapted to be brought alternately into engagement with said gear.

In testimony whereof I affix my signature. 105
JOSEPH CROSSLEY.
